UNITED STATES PATENT OFFICE.

LEOPOLD SIMON, OF NEW YORK, N. Y.

SCREEN.

1,161,077.

Specification of Letters Patent. Patented Nov. 23, 1915.

Application filed May 23, 1914. Serial No. 840,433.

To all whom it may concern:

Be it known that I, LEOPOLD SIMON, a citizen of the United States, residing at New York, in the county of New York and State 5 of New York, have invented certain new and useful Improvements in Screens, of which the following is a full, clear, and exact description, such as will enable others skilled in the art to which it appertains to make 10 and use the same.

This invention relates to screens and, with regard to certain more specific features thereof, to abat-jours or light deflectors of an adjustable character for windows, sky- 15 lights, doors, porches, and building openings generally.

It is one of the objects of the invention to provide a device of the above mentioned nature which will be practical, efficient and reliable in operation.

It is another object of the invention to provide a simple and inexpensive screen comprising a variety of features of adjustability, yet being durable and comparatively 25 inexpensive to manufacture.

It is another object of the present invention to provide a device of the above mentioned general character adapted to exclude or deflect the direct light yet permit the 30 admission of air and reflected or diffused light.

Still another object of the invention is to provide means whereby the device may be rendered inoperative as a screen, and by 35 simple adjustments collapsed into a compact and sightly form.

Other objects of the invention will be in part obvious and in part pointed out herein-after.

40 The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of the invention, Figure 1 represents a porch opening comprising the invention; Fig. 2 is a sectional view taken substantially on the line 2, 2 of Fig. 1; Fig. 3 is a perspective view showing certain details of the invention; Fig. 4 is a view in perspective of the locking mechanism whereby certain movable parts of the frame are detachably se-

cured to the porch or window casing, or skylight wall, or to whatever the screen may be applied; Fig. 5 is a transverse sectional view showing other locking mechanism adapted 60 to detachably secure movable parts of the frame in fixed position; Fig. 6 is an enlarged view of certain of the cord pulleys shown in Fig. 1; Fig. 7 is a detail view of the means for locking or securing the movable frame 65 members in collapsed or compact position.

Referring now more particularly to the drawings wherein similar reference characters refer to similar parts throughout the several views, there is indicated at 1 a porch 70 or window casing having upright members 2 and a connecting member 3 extending between the upper ends of said upright members.

A guiding support 4, preferably in the 75 form of a square bar, extends horizontally between the uprights 2 and is journaled therein, as indicated at 5. This bar is preferably fixed against longitudinal or transverse displacement but is permitted an angular movement by means of the journals mentioned.

Angle members 6 are supported for longitudinal movement or translation on the bar 4 by means of sleeves 7 which preferably correspond in interior peripheral shape to the cross sectional shape of the bar, and these sleeves are adapted to have an easy sliding fit on said bar. In turn these sleeves carry vertical screen connecting members 8, preferably bars, rods or angle irons which have pivotally mounted thereon a plurality of screen supporting members 9 spaced apart substantially equi-distant. These screen supports comprise hollow triangular prisms, 85 preferably of metal, and provided with teeth, as indicated at 10. One side of the prism is adapted to be secured to the vertical members 8, a washer 11 being interposed between each of the members 8 and 100 the member 9 to minimize the friction at the pivot point. Another pair of vertical parallel rods 12 are pivotally connected together by a plurality of screen supporting members 13 similar in construction to the 105 members 9.

It will be noted that by the construction described a plurality of sets of parallel link or parallel rod frame portions are provided which coöperate to support the movable 110 screens which will be hereinafter fully described. For convenience these various

frame portions will be designated as 14, 15 and 16, the frame portion 14 being the one which is secured substantially in fixed relation with the porch 1, the frame portion 16 being the portion which is detachably secured to an opposite side of the porch 1, and movable toward and away from the portion 14 in closing and opening the screen, and the frame portion 15 being an intermediate supporting frame serving, for one purpose, to divide the entire length of the screen into sections, thereby modifying the tendency of the flexible screen members to sag when in operative position.

It will be understood, of course, that the intermediate frame portion 15 is not essential to many of the broader features of the invention.

The movable frame portion 16 comprises locking means preferably disposed at or near the top and bottom of said frame portion. These means comprise a spring pressed detent 17 carried on the frame portion, and which co-operates with the bar 4, and a spring pressed detent 18 secured to one of the uprights 2 of the porch or casing and which co-operates with a stud 19 carried by one of the screen supporting members 9. This stud 19 is formed with an annular groove 20 adapted to engage a locking pin 21 on the detent 18. The stud 19 is also provided with a rounded head 22 adapted to cam its way past the pin 21 compressing the spring 23 in the usual well known manner.

A housing 24 is secured to the sleeve 7 which comprises a part of the frame portion 16 and this housing serves as a chamber for a spring 25 having one end reacting on a wall of the housing and the other end reacting on a collar 27 secured to a stud 28. This stud 28 has an extending portion 29 which serves as a locking pin and is adapted to engage the bar 4 in a recess 30 formed in the latter.

A small bell-crank lever 31 is fulcrumed as indicated at 32 and has a pivotal connection at 33 with the stud 28.

A cord 34 connects with an arm of the lever 31 and provides means whereby the plunger may be retracted against the action of the spring 25, said means being capable of operation at a considerable distance from the location of the detent.

From the foregoing it will be obvious that the frame portion 16 may be secured to or detached from one of the upright members 2 at the will of the operator. The frame portion 14, at the opposite end of the porch opening from the frame portion 16, comprises an angle member 35 secured in a suitable manner to the bar 4 and adapted to have movement therewith as though integral. The parallel rods 12 are pivotally mounted at their upper ends at opposite

sides of the bar 4 on this angle member 35, and accordingly it will be seen that as the bar 4 is rocked the rods 12 are given parallel movement in opposite directions. As has been before stated, the rods 12 are equipped with a plurality of screen supporting members 13. The lowermost one of these is pivotally fixed to the upright 2, as indicated in Fig. 7, at 36. All of the depending vertical frame portions have their upper ends secured to their respective angle members on opposite sides of the bar 4, and accordingly angular movement of said bar causes simultaneously parallel movement of all of the frame portions. The screen members are indicated at 37 and are preferably flexible in order that they may be easily collapsed. In the operative position of the device the screen members 37 extend horizontally, opposite ends of each screen member being provided with pockets 38 within which are inserted wedge-shape blocks 39 corresponding in shape to the interior of the supporting members 9 or 13.

In assembling the device the screen members may be easily slipped in and out of their supports, screws are provided, as indicated at 40, which clamp together the open jaws of the prism thereby securely retaining the screen members in position. The movable frame portions 15 and 16 are free at their lower extremities and weights are provided at 41 and 42 on the frame portions 15 and 16 respectively to prevent undue swinging of these portions when manipulating the device from collapsed to operative position or vice versa.

For the purpose of adjusting the screen members or louver members, as they might be termed, into the various desired light deflecting positions, a handle 43 is provided which may be secured to one of the supports 9 or to any other suitable part of the frame. By moving this handle the particular screen supporting member to which it is attached is given a pivotal movement about the stud 19 through the medium of the parallel rods. The same is imparted through said parallel rods through the sleeve 7 and through the bar 4 to the various other frame portions and screen supporting members of the device. In this manner angular adjustment of all of the screen members may be secured simultaneously.

A pulley 44 is secured to one of the uprights 2, preferably adjacent the fixed frame portion 14, and through said pulley there is reeved a cord 45, one end of which is secured to an angular bracket 46, which in turn is secured to the sleeve 7 of the frame portion 16. The cord 45 extends around another pulley 47 in a pulley block 48 which is secured to the opposite upright 2 of the porch. From this pulley 47 it extends over a pulley 49 in a second block 50 down into a

loop 51 and back over a pulley 52 which is also carried in the block 50 in front of the pulley 49. Thence the cord extends around a pulley 53 and has its opposite end secured to the angle member 46, the whole thereby comprising a tackle whereby the frame portion 16 may be moved back and forth over the bar 4. It will be obvious, of course, that as the frame portion 16 is moved toward the opposite end of the upright opening, it will in due time pick up the frame portion 15 and carry the latter along toward the portion 14. Continuous movement of the portion 16 in this direction causes the three portions to be assembled into a compact arrangement, whereupon a hook 54 (best shown in Fig. 7) may be swung about a pivot 55 on the lower part of one of the supporting members 13 to engage the movable frame portions and secure them in said compact arrangement.

It will be noted that the vertical angle irons 8 which carry the numerous supporting members 9 enjoy a substantially loose relation with the angle member 6 by means 25 of the pin and slot connection indicated at 56. This enables the operator to manipulate the device rapidly to collapse or open the same without danger of breaking the connection between the members 8 and the angle member 6. To render the device more complete and practical as a light deflecting apparatus, screen members 37 are arranged directly below the bar 4 and are connected to the various angle members 6 and 35 by 35 suitable straps or plates 57.

It will be noted that in collapsing the device to render it inoperative as a deflector, there would be a tendency for the flexible screen members to drop below the frame portions subjecting them to dirt and wear and also providing a mass of unsightly appearance. To avoid this there is provided a cord 58 which is connected to the lowermost screen member 37 substantially at the center 45 portion thereof and passed up through the various tiers through a ringbolt or screw-eye 59 secured to the cross-piece 3 of the porch; thence through a similar screw-eye 60 down through the other bank of screen 50 members, the opposite end of said cord being secured to the lowermost screen member of the other bank.

A roller 61 is supported on the sleeve 7 and more directly supported by the angle member 46 thereof. This roller is adapted to intercept the cord 58 as the frame member 16 is moved toward a position of collapse. It will be obvious that as the cord is 55 intercepted and the frame member 16 continues in its path of travel the slack of the flexible screen members will be taken up and the two banks of screen members will be disposed between their adjacent supporting frames in a compact and sightly manner.

Locking means are provided at 63 for se-

curing the screen members in their various positions of angular adjustment. These means comprise an arcuate member 64 provided with a plurality of recesses 65, any one of which is adapted to receive a pin 66 which may be supported for convenience by a chain 67 secured to the upright 2.

An aperture 68 is provided in the weight 42 through which the pin 66 may be inserted and this aperture 68 is moved into alignment with the recesses in the arcuate member 64. If desired, a spring detent may be arranged in position to coöperate with the lower end of the intermediate frame portion 15, as indicated at 69, thereby providing means to rigidly secure this intermediate frame portion in operative position. Guards 70 are provided at either end of the roller 61 to prevent disengagement of the cord 58 with said roller.

The operation of this device is as follows: Assuming the parts to be in the operative position, as shown in Fig. 1, when it is desired to collapse the apparatus the detents 17 and 18 are manually retracted 90 and the cord 45 is operated to move the frame member 16 along the bar 4. As this frame member nears the intermediate member 15 the detent 69 may be manually operated to release this intermediate frame member and the continued operation of the cord will bring all the frame portions into close relationship. As has been previously explained, the roller 60 operating upon the cord 58 takes up the slack of the screen members. The hook 54 may, if desired, be brought into engagement with the movable frame portions to secure the same in compact arrangement. When desired to adjust the device for light deflecting the cord 45 is moved in the opposite direction extending the frame members 15 and 16 progressively until the member 16 reaches the opposite upright 2, whereupon the springs 23 and 25 urge their respective plungers into locking relation with the stud 19 and the bar 4 respectively. The spring pressed detent 69 will also operate to automatically secure the lower part of the intermediate frame portion 15 in its proper and rigid position.

The screen members may then be simultaneously operated to obtain any desired position thereof by means of the handle 43, it being understood, of course, that the frame 16 pivots about the stud 19, and also about the trunnion 5 of the bar 4. When the desired angle of the screen members has been determined by trial, the locking pin 66 may be introduced through the aperture 8 into the recess 65 which is nearest in alignment therewith, thereby securing the screen members in position.

It will be understood that the screen members 37 may be of various constructions and materials capable of effecting the desired

purpose. As shown they are flexible strips of material capable of obstructing or partially obstructing the passage of light, and which may have some light reflecting quality. Canvas is a suitable material for the purpose, but other materials may be used, as wood or metal, under which latter circumstances flexibility may be effected by forming the members 37 of separate wooden or metallic strips joined by a link or other connection permitting the screen members to collapse or fold, and so coöperate with the slack take-up devices.

It will be seen from the foregoing that a device is provided which accomplishes, among others, all the objects and advantages hereinbefore set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:—

1. In a device of the character described, in combination, a horizontal support, a plurality of horizontally disposed flexible screen members, vertical members to which said screen members are attached comprising one translatable on said support, and connecting means between said screen members whereby simultaneous angular movement of said screen members may be effected.

2. In a device of the character described, in combination, a support, a plurality of flexible screen members, members to which said screen members are attached comprising one translatable on said support and having a free end, and connecting means between said screen members whereby simultaneous angular movement may be effected.

3. In a device of the character described, in combination, a horizontal support, a plurality of horizontally disposed flexible screen members, vertical members to which said screen members are attached comprising one translatable on said support and having a free end, and connecting means between said screen members whereby simultaneous angular movement may be effected.

4. In a device of the character described, in combination, a horizontal support, a plurality of horizontally disposed flexible screen members, vertical members to which said screen members are attached comprising one translatable on said support, connecting means between said screen members whereby simultaneous angular movement of said screen members may be effected, and means

adapted to support slack of said screen members when said screen members are collapsed.

5. In a device of the character described, in combination, a support, a plurality of flexible screen members, members to which said screen members are attached comprising one translatable on said support and having a free end, connecting means between said screen members whereby simultaneous angular movement may be effected, manipulative cords adapted to move said translatable member to collapse the screen members, and means adapted to take up slack of said screen members.

6. In a device of the character described, in combination, a horizontal support, a plurality of horizontally disposed flexible screen members, vertical members to which said screen members are attached comprising one translatable on said support, connecting means between said screen members whereby simultaneous angular movement of said screen members may be effected, and means adapted to lock said screen members in different angularly adjusted positions.

7. In a device of the character described, in combination, a horizontal support, a plurality of horizontally disposed flexible screen members, vertical members to which said screen members are attached comprising one translatable on said support, connecting means between said screen members whereby simultaneous angular movement of said screen members may be effected, and lock adapted to secure said movable member in position with the screen members extended.

8. In a device of the character described, in combination, a horizontal support, a plurality of horizontally disposed flexible screen members, vertical members to which said screen members are attached comprising one translatable on said support, connecting means between said screen members whereby simultaneous angular movement of said screen members may be effected, means adapted to translate member to collapse said screen members, and means adapted to secure said movable member in position with said screen members collapsed.

9. In a device of the character described, in combination, a frame comprising a set of parallel rod members adapted to be fixed to a support, a supporting rod and another set of parallel rod members movable on said rod toward and away from said fixed rod members and having their lower ends free, a plurality of collapsible screen members disposed between said sets, means adapted to move said frame to vary the angular position of the screen members, and means adapted to move said movable set to collapse the frame.

10. In a device of the character described, in combination, a frame comprising a rock-member adapted to be journaled in supports, a plurality of sets of parallel rod members

one of which sets is translatable mounted on said rock-member, said sets being spaced apart in operative position, a plurality of transverse screen member supports pivotally secured to the rods of a set, flexible screen members secured to said supports, means adapted to secure said sets in spaced relation, means whereby one of said sets may be moved toward another to collapse 10 the frame, and means adapted to take up the slack of said screen members as said set is moved.

11. In a device of the character described, in combination, a support, a plurality of

frame portions, one of which is slideable on 15 said support toward and from another and comprises a plurality of vertically disposed parallel rods movable relatively to each other transversely of said support, and a collapsible screen member supported by and 20 between said frame portions.

In testimony whereof I affix my signature, in the presence of two witnesses.

LEOPOLD SIMON.
